INVENTOR.

WILLIAM P. COSPER

BY

Ralph W. Brown.

ATTORNEY.

UNITED STATES PATENT OFFICE.

WILLIAM P. COSPER, OF MILWAUKEE, WISCONSIN, ASSIGNEE TO NU-MAT-IK RUBBER
HEEL COMPANY, OF CHICAGO, ILLINOIS, A CORPORATION OF WISCONSIN.

CUSHION HEEL.

Application filed November 21, 1921. Serial No. 516,663.

To all whom it may concern:

Be it known that I, WILLIAM P. COSPER, a citizen of the United States, residing at Milwaukee, in the county of Milwaukee and 5 State of Wisconsin, have invented a certain new and useful Improvement in Cushion Heels, of which the following is a full, clear, concise, and exact description, reference being had to the accompanying drawings, 10 forming a part of this specification.

This invention relates to cushion heels.

It has been found that boots and shoes, as ordinarily constructed with heels of standard forms, do not offer sufficient or proper 15 support for the arch of the foot. This fact is recognized by leading orthopedic experts. The general purpose of the present invention is the correction of this deficiency by the provision of an appliance for external 20 application to a boot or shoe and constructed to afford an additional arch support.

Another more specific object is the provision of a cushion heel having a resilient or yieldable portion adapted to yieldably 25 support the shank of the boot or shoe.

Other objects and advantages will later appear.

One embodiment of this invention is illustrated in the accompanying drawings, in 30 which:

Figure 1 is a sectional view of a cushion heel constructed in accordance with the present invention and shown applied to a shoe of standard form.

Figure 2 is a bottom plan view of the heel of Figure 1.

The heel selected for illustration comprises a body portion 10 having a tread surface 11, and suitably perforated, as at 12, 40 to receive the nails 13 by which it is secured, in the usual manner, to the half-heel 14 of the shoe 15. To increase its cushioning qualities, the heel is preferably provided with a protuberance 16, extending beneath 45 the plane of the tread surface, and with a chamber 17 in the upper portion of the heel to permit the protuberance to yield under the weight of the wearer.

The body portion 10 is of the usual contour corresponding to the shape of the half-

heel 14 and is provided with a forwardly extended portion 18 for engagement with and constituting a support for the shank 19 of the shoe. The portion 18 is preferably of a resilient material and is constructed 55 to extend preferably beneath the plane of the tread surface 11 so that it may assume and sustain part of the weight of the wearer. To this end, the extension 18 of the heel shown is provided with a pair of laterally 60 spaced protuberances 20 projecting beneath the tread surface, and a pair of corresponding chambers 21 above the protuberances permitting the protuberances to yield under pressure.

Thus it will be seen that a device has been provided by which the arch is effectively but yieldably supported. It has been found that the use of a heel, such as that described, adds materially to the ease and comfort of 70 the wearer.

Various changes may be made in the embodiment of the invention hereinabove specifically described, without departing from or sacrificing any of the advantages of 75 the invention as defined in the appended claims.

I claim:

1. A rubber or composition heel having an integral arch support for positioning beneath the rear portion only of a shoe shank, and vertically resilient means on said arch support projecting beneath the plane of the tread surface of the heel for producing an upward pressure upon the shank under the 80 weight of the wearer.

2. A rubber or composition heel having an integral arch support comprising a laterally reduced forwardly extending portion for positioning beneath the rear portion 85 only of a shoe shank, and laterally disposed vertically resilient means on said arch support projecting beneath the plane of the tread surface of the heel for producing an upward pressure upon the shank under the 90 weight of the wearer.

3. A rubber or composition heel having a relatively narrow, laterally extended arch support formed integral therewith, for engagement beneath a shoe shank immediately 100

adjacent the heel and laterally disposed resilient pressure exerting means on said arch support projecting beneath the plane of the tread surface of the heel.

5. 4. A rubber or composition heel having a relatively narrow, laterally extended arch support formed integral therewith, and a

plurality of laterally disposed vertically resilient members on said arch support projecting beneath the tread surface of the heel. 10

In witness whereof, I hereunto subscribe my name this 19th day of November, 1921.

WILLIAM P. COSPER.
